Primary Examiner—Philip S. Hyder

(57) **CLAIM**

I claim the ornamental design for a selectorized dumbbell handle, as shown and described.

DESCRIPTION

FIG. 1 is a perspective view of the selectorized dumbbell handle according to my new design;

FIG. 2 is a top view of the selectorized dumbbell handle of FIG. 1;

FIG. 3 is a bottom view of the selectorized dumbbell handle of FIG. 1;

FIG. 4 is a side view of the selectorized dumbbell handle of FIG. 1;

FIG. 5 is an opposite side view of the selectorized dumbbell handle of FIG. 1; and,

FIG. 6 is an end view of the selectorized dumbbell handle of FIG. 1 (the opposite end view being a mirror image thereof).
